SIGNALING APPARATUS

Ralph M. Showers, Philadelphia, Pa., and August L. Weisbecker, Williamstown, N. J., assignors, by mesne assignments, to the United States of America as represented by the Secretary of the Army

Application April 23, 1948, Serial No. 22,756

6 Claims. (Cl. 116—67)

1

The present invention relates to signaling apparatus such as disclosed in the application of Showers and Chambers, Serial No. 759,580, filed July 8, 1947.

As stated in said application, when canisters and other cargo are discharged from airplanes while in flight, as under wartime conditions, or in inaccessible territory at any time, it is highly desirable that some audible signaling device be associated with the packages so that they may be readily located by the intended receiver on the ground. It is also desirable that the signaling device continue to operate over a considerable period of time so as to afford the ground personnel sufficient opportunity to locate the package, and this without liability of attracting the attention of the enemy if wartime conditions prevail.

It is an object of the present invention, as in the one referred to above to provide a delayed action in the signaling apparatus as well as an intermittent action, but additionally it is an object of the present invention to provide a more compact device and one having more flexibility in the initiation of operation of the device as well as in the time interval between signals.

Other objects and advantages of the invention will be apparent from the following description when taken in connection with the accompanying drawings, in which,

Figure 1 is a plan view of the novel signaling apparatus with parts broken away;

Figure 2 is a vertical sectional view taken on the line 2—2 of Figure 1;

Figure 3 is a sectional view, on a reduced scale on line 3—3 of Figure 4;

Figure 4 is a vertical sectional view through the pulsing and time-delay mechanism;

Figure 5 is a vertical sectional view through the pressure regulator;

Figure 6 is an enlarged sectional view taken on the line 6—6 of Figure 5;

Figure 7 is an enlarged sectional view taken on the line 7—7 of Figure 5;

Figure 8 is a vertical sectional view through the filling and release mechanism in valve opening position, the opposite position being indicated in dotted lines;

Figures 9 and 10 are sectional views taken on the lines 9—9 and 10—10 respectively of Figure 50;

Figures 11 and 12 are detail views of the release-operating mechanism in closed and released positions.

Before describing the structural features of

2

this invention in detail the essential elements will be briefly referred to in their relation to each other. The tank containing the compressed fluid for operating the audible signal is of annular form and is indicated generally by the numeral 1. The space inclosed by the tank 1 is spanned by a plate 2 which forms a foundation for the various operative elements of the combination and which are all supported within the space encircled by the tank 1.

Leading from the main tank 1 is a pipe 3 which communicates with the interior of the release and charging mechanism generally indicated by the numeral 4, and extending from this 15 mechanism is a pipe 5 leading to the interior of a pressure regulator 6. From the interior of the regulator 6 a pipe 7 extends to the interior of the pulsing and time-delay mechanism generally indicated by the numeral 8. Also communicating with the interior of the pulsing and time-delay mechanism as by means of pipe 9 is an auxiliary tank 10 from which the pressure fluid is allowed to feed to the whistle or other audible signal 11. From an inspection of Figure 2 it will be noted that the pipes 3, 5 and 7 as well as parts 20 of the mechanism with which they are associated, including the whistle 11, extend below the base plate 2 and to protect these elements a plurality of downwardly extending arms 12 are riveted or otherwise connected to the base 2 and are united just below the whistle 11 by means of the centrally disposed disc 13. The signaling device may be provided with a pair of straps or other securing means 14 mounted at diametrically opposite points on the exterior of the main tank 1 so that the unit may be readily attached to a canister or other package being discharged from the airplane.

The feeding and release mechanism which is 30 designated generally by the numeral 4 and shown in detail in Figure 8 is mounted on the base plate 2 and comprises a cylindrical member 20 having an open lower end seated upon a gasket 21 mounted in an annular receiver 22 secured to the base plate. Threaded to the interior of the member 20 is a cylindrical element 23 provided with a conventional type of tire valve 24 at its upper end and extending through the base plate 2 at its lower end where it is provided with a lateral opening to receive an end of the pipe 3. Encircling the lower end of the tubular member 23 is a cup-shaped member 25 provided with a lateral opening to receive one end of the pipe 5 which leads to the pressure regulator and the upper end 35 of this cup-shaped member extends upwardly

through the base plate 2 and communicates with the interior of the tubular member 20 by means of a passageway 26 extending downwardly through an enlargement on the tubular member 23.

This tubular member 20 is provided with a circular enlargement at its upper end from which radiate a pair of fixed pins 27 and which serve as guides for a vertically slidable sleeve 28 which is provided with diametrically opposed slots 29 to receive the guide pins 27. This sleeve 28 is normally biased downwardly toward the base plate 2 by means of a coil spring 30 which bears at its upper end against the circular enlargement of the tube 20 and at its lower end against an in-turned flange 31 on the lower end of the sleeve.

Threaded to the interior of the upper end of the slidably mounted sleeve 28 is a disc 32 provided with a centrally located and downwardly extending pin 33 which is adapted to pass through the enlarged head of tube 20 and to be received in the upper end of valve element 24 to move the valve from its seat. A gasket 32' on the under side of disc 32 cooperates with a conical seat 33' on the upper surface of the head of tube 20 to seal off the escape of fluid through the head when the valve 24 is opened by the insertion of pin 33. The operating means for setting the sound device in operation consists of a bifurcated rod 34 fixed to the exterior of the member 28 as indicated by numeral 35. This rod is provided with an offset portion extending through the plate 2 and with an extension 34'. A latch 36 pivoted to a guard arm 12 cooperates with the extension 34' to normally hold the rod 34 in raised position as indicated in Figure 11, and consequently prevents opening of the valve 24. A cord 36' secured to the latch 36 provides the necessary means for releasing the latch when the signaling apparatus is to be put into operation. The released position of the latch is clearly indicated in Figure 12, and it will be obvious that the valve 24 may be readily closed by raising the rod 34 and swinging the latch 36 to the position indicated in Figure 11. When the arm 34 is raised and held in raised position by the element 36 the pin 33 will be removed from the valve 24 as indicated in dotted lines in Figure 8. When, however, the arm 34 is released by operation of the element 36 the spring 30 will force the sleeve 28 and arm 34 downwardly and will thus force the lower end of the pin 33 into cooperative relation with the valve 24 so as to remove it from its seat and permit the compressed fluid in the interior of tube 23 to escape and pass downwardly through the passageway 26 to the interior of the cup shaped member 25 and thence to pipe 5 and to the pressure regulator 6. When it is desired to refill the main tank 1 this operation may be accomplished by unscrewing the tubular member 20 and removing it and its related parts from the valve element 23-24 thereby giving access to the valve 24 so that an ordinary pressure nozzle may be applied thereto for the purpose of recharging the tank 1 with the particular fluid employed to supply the mechanism.

As heretofore mentioned the pressure regulator is indicated generally by the numeral 6 and is shown in detail in Figure 5. This regulator comprises upper and lower cup shaped members 43 and 41 threadably connected as indicated by the numeral 42 and having clamped between them a flexible diaphragm 43. Formed centrally of the member 40 is an upward tubular extension 44 in which is mounted a compression spring 45 having 75

its lower end seated in a cup 46 supported on the diaphragm 43 and its upper end in engagement with a disc 47 threaded into the upper end of the sleeve 44 and providing means for adjusting the compression spring on the upper side of the diaphragm. The lower member 41 is provided with a centrally disposed and downwardly directed tubular member 48 provided with a transverse partition 49 adjacent its upper end. This partition is provided with a circular passageway 50 (Figure 6) through which extends the squared rod 51 into engagement with a valve 52 which latter is adapted to cooperate with the partition 49 to shut off the passage of fluid from the interior of the tubular member 48 to the interior of the pressure regulator. This valve element 52 is normally biased toward its seat by means of a compression spring 53 which has its upper end in engagement with the valve body and its lower end in engagement with a plug 54 threaded to the interior of the member 48. A guiding and supporting member 55 of hexagonal cross-section is secured to the upper end of the rod 51 and is slidably mounted in the circular portion of the constricted upper end of the tubular member 48 and contacts the lower surface of the diaphragm 43. By reason of the hexagonal shape of the member 55 in cooperation with the circular interior of its guiding support the pressure fluid passing upwardly around the squared rod 51 may also pass around the hexagonal member 55 to the interior of the pressure regulator and thence through the pipe 7 to the interior of the pulsing and time-delay mechanism 8. It will be understood, of course, that when the pressure on the underside of the diaphragm 43 exceeds that for which the springs 45 and 53 are adjusted the diaphragm will be raised and permit the valve body 52 to engage its seat and thus prevent the admission of further fluid to the interior of the regulator.

The pulsing and time-delay mechanism 8 is shown in detail in Figures 3 and 4 and comprises a cylindrical block of metal 60 provided with circular depressions 61 in its upper and lower ends. 45 These cavities are inclosed by upper and lower caps 62 and 63 which are also provided with cavities in alignment with the cavities 61 so as to provide pockets or chambers for upper and lower diaphragms 64 and 65 which are clamped between the caps and the ends of the body 60 of the pulsing and time-delay device.

The pipe 7 is connected to the body member 60 by means of a coupling 66 which communicates with a horizontal passage 67 in the member 60. 55 This passageway 67 communicates with a vertical passageway 68 in the body member 60 leading to the upper pocket 61, and with a horizontal passageway 69 in which is mounted an adjustable valve 70. The passageway 69 is provided with a narrowed inner end 71 and this passage is controlled by the valve 70. The passageway 71 communicates with a vertical passage 72 which latter communicates with the upper pocket 61. The lower end of the passage 72 communicates with a horizontal pocket 73 in the body member 60 and in which is mounted an adjustable valve 74. The horizontal pocket 73 is provided with a narrowed exit 75 the extent of opening of which is controlled by the valve 74 and this narrowed passageway communicates with a circular pocket 76 which in turn communicates with a coupling 77 for the pipe 9 which leads to the auxiliary tank 10. Extending downwardly from the circular pocket 76 is a passage 78 communicating with the lower pocket or chamber 61.

The diaphragm 64 normally seats upon the upper end of a tubular extension 80 surrounding the passageway 63 and thus seals this passageway. Upon the upper side of the diaphragm 64 a circular metal disc 81 is secured and the disc and diaphragm are normally pressed against the tubular extension 80 by means of a coil spring 82 positioned in a metal tube 83 threaded into the cap 62 and extending outwardly therefrom. The lower diaphragm 65 normally seats upon the outer end of a circular extension 84 on the lower side of the body member 68 to seal off communication between the passage 78 and the interior of extension 84. This diaphragm is provided with a circular metal disc 85 on its lower surface which disc is engaged by a compression spring 86 mounted in a whistle element 11 threaded into the lower cap 63. The diaphragm 65 differs from the diaphragm 64 in that it is provided with a central opening through which extends a hollow tubular member 88 which provides communication between the lower pocket 61 and the interior of the whistle member 11, and the latter is provided with an exhaust opening 89 in its lower end.

In the operation of this element of the signaling apparatus, that is, the pulsing and time-delay device, the pressure fluid enters through the passage 67 the opening of which is controlled by the adjustable valve 70 and passes up through the passageway 63 to impinge against the lower surface of the diaphragm 64. A small amount of the fluid pressure, depending upon the adjustment of valve 70, also passes through the passage 71 downwardly through the passage 72 past the adjustable valve 74 into the passageway 75, pocket 76, coupling 71, pipe 9, to the auxiliary tank 10. When the pressure against the under surface of the diaphragm 64 builds up to the maximum for which it is adjusted the diaphragm rises against the pressure of the compression spring 82 and the fluid may then travel at a much faster rate from the pocket 61 and the full length of the passage 72 to the auxiliary tank 10. It will be understood, of course, that the whistle cannot operate until the lower diaphragm 65 is removed from its seat on the circular extension 84 and this movement cannot take place until pressure is built up in the auxiliary tank sufficiently to move the diaphragm from its seat. Thus the relatively slow feeding of the pressure fluid through the passageway 71 provides for a delayed action of the whistle at the initiation of the operation when the operating lever 34 is moved to open the valve 24 in the release and filling mechanism 4. When the pressure builds up in the auxiliary tank 10 to the degree required to depress the lower diaphragm 65 the latter will be moved from its seat and a modicum of the fluid pressure will escape from the pocket 61 past the lower edge of the tubular extension 84 and thence through the hollow tubular member 88 to the whistle 11 to sound the signal. This escape of fluid reduces the pressure in the reserve tank 10 and also on the upper side of the diaphragm 65, and the spring 86 will cause it to seat upon the lower end of the tubular extension 84 to shut off operation of the whistle until pressure again builds up in the auxiliary tank sufficiently to repeat the operation. This operation of the diaphragm 65 provides a pulsing action which in turn produces an intermittent whistling sound both of which will continue until the pressure in the system as a whole drops below that required for operating the diaphragm 65 or until the lever 34 is operated to withdraw the pin 33 from its operative relationship with the valve 24.

The operations of the various elements have been described in connection with the description of the structural details of the elements and need not be further dwelt upon except in a general way as they relate to the operation of the signaling device as a whole.

In this general operation of the signaling apparatus it is, of course, first secured by the straps 14 to the package to be dropped from the airplane and to be later located upon the ground through the medium of the intermittent whistling action. As the package or other cargo to which the signaling device is attached is discharged from the vehicle the element 36 is operated to depress the lever 34 and thereby force the pin 33 into the valve 24 to open the same. When this operation is effected the interior of the valve casing 23 is in communication with the main pressure tank 1 through the medium of the pipe 3 and this pressure fluid will pass through the valve 24 downwardly through the passage 26 into the cap 25 and thence through the pipe 3 to the pressure regulator 6. As the pressure builds up within the regulator 6 to raise the diaphragm 43 the pressure fluid will pass therefrom into the pipe 7 and to the pulsing and time-delay mechanism 8. If the pressure within the regulator 6 becomes too great the diaphragm will be raised a sufficient distance to permit the valve 52 to engage its seat, thereby shutting off further entrance of the pressure fluid into the pressure regulator until a sufficient amount of the fluid in the auxiliary tank 10 has been consumed so as to substantially lower the pressure within the regulator 6.

The extent of time-delay required in the matter of initiating the operation of the intermittent whistle may vary under certain conditions and to provide this variation the valve member 76 is adjusted inwardly or outwardly to vary the extent of opening of the passageways 67 and 71 so as to vary the time required to build up the pressure within the auxiliary tank 10 to depress the diaphragm 65 and operate the whistle. It is also desirable under certain conditions to vary the extent of time between pulsations of the diaphragm 65 and the attendant operations of the intermittent whistle, and to this end the valve member 74 may be adjusted to vary the extent of opening in the passage 75, thereby varying the time required to build up maximum pressure in the auxiliary tank 10 after each single operation of the whistle. By these several adjustments it will be seen that the overall period of operation of the intermittent whistle may be substantially varied and the initial operation of the whistle may also be varied, thereby conserving pressure fluid and permitting the ground personnel a greater period of time in which to locate the cargo to which the signaling mechanism is attached.

If it is desired to re-use the signaling mechanism the same may be recharged as hereinbefore indicated, that is, by removing the cylindrical member 20 so that a pressure hose may be applied to the valve 24 to supply the necessary pressure fluid to the tank.

In accordance with the patent statutes we have described what we now consider to be the preferred embodiment of the invention but it is quite apparent that many of these structural details may be substantially varied without in any way departing from the spirit of the invention and it is intended that all such structural altera-

tions be included within the scope of the appended claims.

We claim:

1. An audible signaling apparatus comprising a fluid-operated sounding device, a tank of pressure fluid associated with the sounding device for operating the same, releasable means for maintaining the apparatus inoperative, means for delaying the operation of the sounding device after the releasable means is operated, and means for varying the extent of delay.

2. An audible signaling apparatus comprising a fluid-operated sounding device, a tank of pressure fluid associated with the sounding device for operating the same, releasable means for maintaining the apparatus inoperative, means for delaying the operation of the sounding device after the releasable means is operated, and an adjustable valve for varying the extent of delay.

3. An audible signaling apparatus comprising a fluid-operated sounding device, a tank of pressure fluid associated with the sounding device for operating the same, means connected with said tank for intermittently feeding compressed fluid to said sounding device, releasable means for maintaining the apparatus inoperative, means for delaying the operation of the sounding device after the releasable means is operated, means for varying the extent of delay, and means for varying the rate of flow of the fluid to the sounding device.

4. An audible signaling apparatus comprising a fluid-operated sounding device, a tank of pressure fluid for operating the sounding device, means connected with said tank for intermittently feeding compressed fluid to said sounding device, releasable means for maintaining the apparatus inoperative, means for delaying the operation of the sounding device after the releasable means is operated, an adjustable valve for varying the extent of delay, and an adjustable valve

for varying the rate of flow of the fluid to the sounding device.

5. An audible signaling apparatus comprising an annular tank of pressure fluid, a fluid-operated sounding device and a curved auxiliary tank snugly fitted within the space encompassed by the annular tank, connecting means between the annular and auxiliary tanks, and means connected with the auxiliary tank for intermittently feeding a portion of the fluid from the auxiliary tank to the sounding device.

6. An audible signaling apparatus comprising a fluid-operated sounding device, a tank of pressure fluid for operating the sounding device, means connected with the tank for intermittently feeding compressed fluid to said sounding device, releasable means for maintaining the apparatus inoperative, an adjustable valve in the feeding means for delaying the operation of the sounding device after the releasable means is operated, and a second adjustable valve in the feeding means for varying the intervals between operations of the sounding device.
